PROTECTIVE COVERING

William C. Harben, Lake Worth, Fla., assignor to
 Vacuum Grip Cover Company, Inc., Bridgeport,
 Conn., a corporation of Connecticut

Application June 4, 1947, Serial No. 752,349

1 Claim. (CL 154—50)

1

This invention relates to protective coverings and has particular reference to coverings employed to protect highly finished surfaces from scratching or scuffing.

An object of the invention resides in the provision of a covering formed of flexible and resilient material of such nature as to conform generally to various irregular surfaces to be protected, such as vehicle fenders, vehicle seats or to other articles having a highly finished surface to be protected against marring or soiling.

A further and very important object of the invention resides in the detail construction of the covering, whereby it is frictionally held against slipping on a polished surface, will not wrinkle or roll with body motion, is readily and easily cleaned and may be used with or without a non-absorbent covering.

A particularly outstanding object of the invention is the construction of the protective covering having its surfaces calendered and provided with a multiplicity of minute shallow air pockets which, when slight pressure is placed thereon, causes the cover to adhere to a polished surface against slipping or crawling.

Other objects of the invention will readily present themselves during the course of the following description, reference being had to the accompanying drawings.

In the drawings:

Figure 1 is a perspective view of a protective cover, constructed in accordance with the invention,

Figure 2 is a fragmentary perspective view of a slightly modified form of the invention,

Figure 3 is a perspective view of the cover with a part thereof removed,

Figure 4 is a fragmentary enlarged section taken on line 4—4 of Figure 3 and,

Figure 5 is a fragmentary enlarged plan view of one of the identical sides of the cover.

Like numerals are employed to designate like parts throughout the several figures of the drawing.

Referring specifically to the drawings, the numeral 6 designates a protective cover as a whole, embodying a rectangular sheet of flexible and resilient material 6, having upper and lower calendered surfaces 7 and 8. The calendered surfaces 7 and 8 are provided with a multiplicity of relatively small and closely arranged shallow air pockets 9 and 10 over its entire area and closely arranged. The body 6 is formed of a non-absorbent sponge rubber or the like and, when pressure is placed thereon, causes the suction cups to grip

2

or adhere to the surface to be protected. Grommets 11 are provided adjacent each corner of the sheet 6, for a purpose to be described.

Referring to Figure 1, the numeral 12 designates a sheet of relatively thin, non-elastic, non-porous plastic film, that is co-extensive with the cover 6 and provided with grommets 13 adjacent each corner to lie in registry with the grommet 11. Tie cords or tapes passing through the grommets, as at 14, serve to secure the sheets 6 and 12 together and in alignment. While four grommets are illustrated for both the sheet 12 and cover 6, it is obvious that additional ones may be employed if found desirable. The purpose of the sheet 12 is to provide a protective non-porous, but flexible covering for the cover 6, especially, when the cover is employed in automotive work, to maintain the cover free from grease, etc. The sheet 12 may be transferred to the opposite side 10 of the cover 6 when a clean surface is required. It is apparent that the cover may be utilized without the sheet 12, in which case the operator merely unties the tapes 14 and removes the sheet, working at such times directly on one of the calendered surfaces. As the surfaces 7 and 8 become soiled, they may be readily and easily cleaned.

It may be found desirable in certain cases to provide the cover 6 with a permanent protective sheet and, to this end, a sheet 12a, see Figure 2, is secured to the cover 6 in any convenient manner, as by stitching 15 around its marginal edges. It may be found desirable also, to cement the sheet 12a upon the cover 6 in lieu of the stitching.

35 In use, the cover is spread upon or over the object to be protected, such as a vehicle fender. A slight pressure or smoothing action causes the suction cups to grip the smooth finished surface. This gripping prevents the cover from creeping or sliding on the fender from body motion of the operator and the resilient body of the cover will absorb the blows of tools or other equipment laid thereon. When the cover is used without the sheet 12, it will be found that tools laid thereon will not slide and become misplaced as is so common with covers heretofore employed. The cover, while being flexible and resilient, will not roll or wrinkle in use to conceal small parts or tools. If desirable, any suitable indicating mark may be printed or stencilled on one side of the cover to indicate to the operator the side upon which he has been working, thus keeping the clean side always toward the finished surface. The sheets 12 or 12a are not affected by gasoline, oil, grease, 40 battery acids or brake fluids and, when soiled,

may be readily cleaned by a light sponging with gasoline or mineral spirits. The cover while primarily designed as a protective cover for auto fenders, has many and varied uses. As a protective covering to be used by a mechanic in driving a vehicle, it will be found that the cover will lie snugly upon the upholstery and maintain its position against slipping or sliding, regardless of the movements of the driver. The identifying mark upon one side of the cover will be particularly valuable to the driver in determining which side of the cover to place against the upholstery.

It will be seen from the foregoing that an extremely simple and highly desirable cover has been provided. The cover is economical in use, resulting in a considerable saving in laundry costs, is cheap to manufacture, has a remarkable toughness against wear and is efficient to a high degree.

It is to be understood that the invention is not limited to the precise form shown, but that it includes within its purview, whatever changes fairly come within either the terms or the spirit of the appended claim.

Having described my invention, what I claim is:

A flexible protective covering adapted to conform generally to irregular surfaces such as ve-

hicle fenders and vehicle seats to protect the same against marring or soiling which comprises, a thin flexible sheet of sponge rubber having opposite faces provided with a multiplicity of small suction cups closely arranged and extending over the full area of the faces, and a thin flexible sheet of non-porous plastic material covering one face of said sponge rubber sheet and coextensive therewith, the remaining face of said sponge rubber sheet being exposed, said sheets being secured together only at their marginal edges.
